UNITED STATES PATENT OFFICE.

EDWARD SCOTT STEWART AND CHRISTOPHER DOUGLASS STEWART, OF OTTAWA,
ILLINOIS.

TELEPHONE.

1,138,698.

Specification of Letters Patent. Patented May 11, 1915.

Application filed May 26, 1913. Serial No. 769,887.

To all whom it may concern:

Be it known that we, EDWARD S. STEWART and CHRISTOPHER D. STEWART, citizens of the United States, residing at Ottawa, in the 5 county of La Salle and State of Illinois, have invented a certain new and useful Improvement in Telephones, of which the following is a full, clear, concise, and exact description, reference being had to the accompanying drawings, forming a part of 10 this specification.

Our invention relates to telephones and has for its object the provision of a combined telephone transmitter and receiver, 15 which in the form herein shown is of great use as a lineman's test telephone, although of course our invention is not to be limited to such use alone, as it has various and many applications and may be suitably 20 modified for further and other applications without departing from the spirit of our invention herein disclosed.

Generally speaking our invention contemplates a telephone receiver having a diaphragm, which diaphragm in addition to transmitting sound waves received by the receiver in the form of electric undulations, also serves as the diaphragm for a transmitting element, which transmitting element 25 the diaphragm actuates by virtue of confined air within a suitable chamber.

We will explain one form of carrying out our invention by referring to the accompanying drawing, in which—

35 Figure 1 is a front view of a telephone constructed in accordance with our invention; Fig. 2 is a longitudinal sectional view thereof; Fig. 3 is a rear view thereof, and Fig. 4 is a sectional view at right angles to 40 that of Fig. 2.

In the form herein shown our invention contemplates a shell or cup 1 provided with a cap 2 having screw threaded engagement with the cup. Within the shell we mount a 45 pair of magnetic pole pieces 3, 3, which carry a receiver coil 4. A permanent magnet forming part of the entire circumference of a circle unites the pole pieces 3, 3 so that these pole pieces together with the permanent magnet 5 and the coils 4, 4 form a receiver in connection with the diaphragm 6, which diaphragm is held in place between the cup 1 and the cap 2. The rear extremity of the cup 1 has an opening 7, against which 55 opening a mica diaphragm 11 is placed. An

annular insulating washer 8 is placed between an insulating cover 9 and the mica diaphragm 11, and is suitably held in place by the strip 10. Between the metal cup 9 and the insulating washer 8 a mica dia- 60 phragm 11 is placed and suitably held, which mica diaphragm carries a carbon electrode 12. A further electrode 13 is mounted in the rear of the cup 9 and between the two electrodes granular carbon 14 is placed. 65 A transmitting element is thus formed upon the back of the receiver cup 1 and insulated therefrom. The movable electrode 12 of this transmitting element is thus in contact with the air in the confined space within the cup 1. Now whenever the diaphragm 6 is actuated by talking against it from without the device, the confined air will be agitated, thus to vibrate this movable electrode 12 to 70 actuate the transmitting element. Two circuit terminals 15 and 16 are provided so that the circuit extends, say from the terminal 16 by means of conductor 17 to the metal cover 9, through the transmitting element, to the electrode 12, then by means of 75 the conductor 18 to one of the coils 4, then through the other coil 4, and then by means of the conductor 19 to the other terminal 15, the receiving and transmitting elements thus being in series similarly to the ordinary direct current receiver. Under certain circumstances therefore, of course, the permanent magnet 5 might be dispensed with. It will be thus seen that the diaphragm 6 serves two purposes. First to 80 transform the electrical undulations of the coils 4 into sound waves and to actuate the transmitting element to cause electrical undulations through the interposition of the confined air within the device. 85

It is thought from what has been described that the operation of our improved device will be clear and that it will also be clear that the particular illustration used is illustrative merely of one form of carrying out our invention.

Having however thus described this particular form of carrying out our invention, what we claim as new and desire to secure by Letters Patent is:

1. A device of the character described comprising a diaphragm, an electromagnetic receiver winding for actuating said diaphragm, a variable resistance transmitting element, and an air confining casing to 110

which said transmitting element and diaphragm are mounted so that said diaphragm when actuated by sound waves actuates said transmitting element through the agency of the air confined within said casing, said transmitting element having a fixed electrode rigidly mounted on said casing and a movable electrode, and said casing having an opening therein registering with said movable electrode.

2. A device of the character described comprising a diaphragm, an electromagnetic receiver winding for actuating said diaphragm, a variable resistance transmitting element, and an air confining casing to which said transmitting element and diaphragm are mounted so that said diaphragm when actuated by sound waves actuates said transmitting element through the agency of the air confined within said casing, said transmitting element having a fixed electrode rigidly mounted on said casing and a movable electrode, and said casing having an opening therein registering with said movable electrode and closed by said transmitting element.

3. A device of the character described comprising a diaphragm, an electromagnetic receiver winding for actuating said diaphragm, a transmitting element, and an air confining casing to which said transmitting element and diaphragm are mounted so that

said diaphragm when actuated by sound waves actuates said transmitting element through the agency of the air confined within said casing, said transmitting element having a movable electrode and a carbon chamber provided with comminuted material, said chamber being fixedly mounted on the casing and said casing having an opening therein registering with said movable electrode and closed by said transmitting element.

4. A device of the character described comprising a casing, a diaphragm mounted on said casing, and forming a substantially air-tight compartment with said casing, a receiver magnet mounted within said casing to actuate said diaphragm, and a carbon carrying cup rigidly mounted on said casing and having a movable electrode actuated by said diaphragm through the air confined within said casing when said diaphragm is under the influence of sound waves exteriorly of said casing.

In witness whereof, we hereunto subscribe our names this seventh day of May, A. D. 1913.

EDWARD SCOTT STEWART.
CHRISTOPHER DOUGLASS STEWART.
